NATHAN S. CLEMENT, OF NORTHAMPTON, MASSACHUSETTS.

Letters Patent No. 101,228, dated March 29, 1870.

IMPROVED MACHINE FOR NICKING SCREWS.

The Schedule referred to in these Letters Patent and making part of the same.

I, NATHAN S. CLEMENT, of Northampton, in the county of Hampshire, State of Massachusetts, have invented certain Improvements in Machines for Nicking Screws, of which the following is a specification, reference being had to the accompanying drawings, in which—

Figure 1 is a side elevation of my invention;

Figure 2 a top view; and

Figures 3, 4, 5, 6, and 7, detached views of the various parts of the same.

Similar letters of reference indicate like parts.

My invention consists in the employment of a carriage provided with automatic clamping devices which hold the blanks, while the carriage carries them by a series of stationary cutters which nick the heads of said screws, and then releases them and allows them to be discharged over an inclined apron.

It also consists in the peculiar arrangement of the hoppers, taking-up fingers, and track for feeding the screws to said carriage all as hereinafter more fully described.

A designates the hopper, the bottom of which is semicircular and provided with an opening or slot, b, on the back side, sufficiently wide to allow the body of the screws to pass through it.

The screws or screw-blanks are placed promiscuously in the hopper A, and taken up by the fingers a a, which are attached to the inside sides of the revolving annular rims d d', and immediately above the center of the hopper A, so that both the hopper and rims have a common axis or center.

As the fingers a a revolve, a number of the screw-blanks are caught between them by their heads, while the motion of the fingers a a, through the hopper A, will cause the bodies of many of the blanks to extend through the slot b, in such position that their heads will be caught by the next pair of fingers.

When said fingers reach the point, or about that point, indicated in fig. 1, the screw-blanks slide downward into the track B, the upper end of which track is curved inward at s, so that the inner ends of the fingers a a will, in the progress of their revolution, meet the upper end of track B, as shown in fig. 2. The blanks then work down the track B, in the usual manner, until the same is filled.

C designates the main shaft, to which the motive power is applied.

On one end of shaft C is a crank-pin, c, on which is arranged an ordinary slotted and pivoted lever, e, connected, by pitman f, to levers g, on which is the pawl h, which operates the ratchet-wheel D, which ratchet-wheel is secured to the same shaft as are the rims d d'.

To the opposite end of the shaft C is attached a beveled gear, indicated by broken lines in fig. 1, which

meshes into gear E, which gear E is secured to the carriage F.

The carriage F is provided with spring jaws i i, a detached end view of which is shown in fig. 6.

On one side of the jaws i i is a sliding wedge, j, which is connected to a screw, k, provided with dogs l l', and a spring, u. A side elevation of said wedge, screw, dog, and spring is shown in fig. 5.

The dog l l' is fitted so as to turn on the end of the screw k, and is held on by pin x. One end of spring u is passed through the dog l, while the other end is secured to the screw k.

A small cap, m m, is placed over the jaws i i and wedge j, to hold the same in place.

For different-sized screws, jaws of different thicknesses can readily be inserted.

As the carriage F revolves, the dog l strikes the trip n, which may be provided with a friction-roller, if desired and turns said dog, when the end of the spring u strikes the pin x, and thus gives a positive motion to the screw k and withdraws the wedge j, which allows the jaws i i to open, and, as they pass under the end of the track B, the lower screw-blank falls into them.

Fig. 7 is a front elevation of the lower end of the track B, with the cap y removed.

The adjustable or spring foot r, which is secured to the lower end of track B, extends partially over the carriage F, and prevents the blank from raising out of the jaws i i until the dog l strikes the trip o, (see fig. 2,) and, by means of the spring u, turns the screw k inward, and presses in the wedge j until the jaws i i firmly gripe the screw-blank, when the spring will yield, and allow the dog l l' to turn without further turning the screw k, thus accommodating the slight variations in the size of the screw-blanks.

As the carriage F passes on, the head of the blank soon strikes the first tooth in the series of stationary cutters G, and a light chip is planed out of the nick. Each successive tooth of the cutters G being a little longer than the one preceding it, the head of the screw-blank is properly nicked by the time it has passed the last tooth of cutters G.

A similar series of cutters might be arranged on a straight line, while the screw-blanks could be carried by the cutters on an endless apron, the operation of which cutters would be substantially the same as above described.

The trip n opens the jaws i i, as before described, and releases the blank, when its head is immediately caught by the inclined apron p, and rides up the same out from between the jaws i i, which jaws will be ready to receive another blank as they again pass under the track B.

On the rims d d' I have shown only one pair of

fingers, and in the carriage only one pair of jaws, but these parts can be duplicated as many times as may be desired.

The take-up fingers *a a* should be of such length that their ends will nearly reach the slot *b* in the hopper *A*, but should not extend through the same, by which arrangement a smaller hopper can be used, as the body of the screws will be placed in the best possible position to be taken up by the fingers *a a*.

The peculiar form of the fingers, and the position in which they are set, causes the screw-blanks to be discharged before the fingers have passed once around the axis on which said fingers revolve, as clearly shown in fig. 1.

By making the inward curve *s* on the upper end of track *B*, and this peculiar form of fingers, I am enabled to place as many pairs of fingers on the rims *d d'* as may be desired.

The fingers are adjustable for screw-heads of different sizes, as follows:

The rim *d'* is rigidly secured to the same shaft as is the ratchet-wheel *D*. Immediately back of rim *d'* is a collar, *q*, which is connected with rim *d* by means of pins *r r r* which pass through the rim *d'*. As the fingers *a a* are secured to the rims *d d'*, slipping the collar *q* upon the shaft and securing the same in place by set-screw, or its equivalent, the rims and fingers can be opened or closed to accommodate screws of different sizes.

The adjustable foot *r* of the track *B* not only serves to hold the screws in the jaws *i i* until they are closed, but it should be of thin flexible metal, sufficiently rigid to hold the screws in the track in ordinary cases, but yielding enough to allow a screw-blank to pass out, in case the same should not properly enter the jaws *i i*.

The series of stationary cutters *G* are formed in segments, with one or more teeth on each, so that, as the ends of said teeth wear and are sharpened, the same can be adjusted outward more or less as desired.

The last tooth in the series of cutters *G* should be placed so as to come nearly in contact with the in-

side edge of the carriage *F*, which arrangement will prevent the chips from rolling up and clinging to the screw-head.

Although I consider it preferable to use the stationary cutters *G*, a solid revolving cutter might be used on this machine, by causing it to revolve on a different axis from that of the carriage, as shown in fig. 4.

The base *H* is intended to be of cast metal, and cored out hollow, with a central hub, in which is keyed a shaft, so as to be raised and lowered, but not to revolve. The upper end of said shaft is tapering, and the carriage *F* revolves on the same.

By raising and lowering the shaft it can be made to properly fit the carriage *F* without changing the position of the latter. Immediately under the cutters *G* are suitable holes, to conduct the chips and soda-water used in nicking to the interior of the base *H*, as indicated by broken lines in fig. 1.

I claim as my invention—

1. The combination of the series of stationary cutters *G*, carriage *F*, and an automatic gripping mechanism, substantially as and for the purpose described.
2. The combination of the carriage *F*, jaws *i i*, wedge *j*, screw *k*, dog *l l'*, spring *u*, and trips *n* and *o*, all arranged to clamp and release the screw, substantially as described.
3. The inclined apron *p*, in combination with the carriage *F*, and arranged so as to raise the screws from out of the jaws *i i*, as described.
4. The combination of the fingers *a a*, rims *d d'* or their equivalents, and the curve *s*, in upper end of the track *B*, all arranged so that the fingers revolve in a direct line with the upper end of the track *B*, and meet the same at a point between the outer ends of said fingers and the axis on which they revolve.
5. The combination and arrangement of the fingers *a a*, rims *d d'*, and collar *q*, for adjusting the fingers to different-sized screws, substantially as described.

NATHAN S. CLEMENT.
